UNITED STATES PATENT OFFICE.

MATTHEW NIAL, OF BROOKLYN, NEW YORK.

FLYING-MACHINE.

No. 851,895.

Specification of Letters Patent.

Patented April 30, 1907.

Application filed October 14, 1905. Serial No. 282,709.

To all whom it may concern:

Be it known that I, MATTHEW NIAL, a citizen of the United States, and a resident of Brooklyn, in the county of Kings and State of New York, have invented certain new and useful Improvements in Flying-Machines, of which the following is a specification.

The invention relates to improvements in flying-machines, and it consists in the novel features, arrangements, construction and combinations of parts hereinafter described and particularly pointed out in the claims.

The object of the invention is to produce a novel and efficient flying machine of simple and durable construction and possessing a number of wings at opposite sides thereof and arranged one above another, with means under the control of the operator for actuating said wings to elevate and propel the machine.

The machine is also provided with suitable means for steering the same.

The invention will be fully understood from the detailed description hereinafter presented, reference being had to the accompanying drawings, in which:

Figure 1 is a top view of a machine constructed in accordance with and embodying the invention, a few of the middle wings being partly broken away for clearness of illustration; Fig. 2 is a vertical longitudinal section of same on the dotted line 2—2 of Fig. 1; Fig. 3 is a vertical transverse section of same on the dotted line 3—3 of Fig. 1; Fig. 4 is an enlarged top view of one of the standards to which the wings are hinged, a portion of the wings being illustrated; Fig. 5 is a vertical section of same on the dotted line 5—5 of Fig. 4; Fig. 6 is an enlarged horizontal section through a portion of the machine on the dotted line 6—6 of Fig. 3, and Fig. 7 is an enlarged edge view of one of the wings.

The body of the machine comprises a series of U-shaped frames 10, arranged in parallelism and at suitable distances apart, the vertical members of said frames being designated by the numeral 11 and affording standards extending upwardly along each side of the machine. The standards 11 are connected at their upper ends, along each side of the machine, by rods or tubing 12, and adjacent to their lower portions by means of rods or tubing 13. The horizontal members of the frames 10 are connected by longitudinal sills or beams 14 which are preferably of wood set on edge.

The U-shaped frames 10 are preferably

each in one integral piece and formed from tubing which is square or rectangular in cross-section, as more clearly illustrated in Figs. 4 and 6, the frames thus constructed being very strong and not of unnecessary weight, and in addition they provide suitable supports for the pivots of the wings 15, by which the machine is propelled. The standards 11 formed by the frames 10 are kept parallel with each other and properly braced by means of the rods or tubes 12, 13, which extend lengthwise of the machine. I shall preferably brace some or all of the standards 11 by means of transverse rods or tubes 16 (Fig. 3) extending transversely of the machine and connecting said standards.

The general machine will be provided with suitable supporting wheels 17 of usual character, and at a suitable point in the bed of the machine the latter will be furnished with a seat 18 for the operator, which seat will be mounted upon tracks 19 so that it may have a longitudinally sliding movement, as required and for the purposes hereinafter explained.

At the forward end of the bed of the machine I provide a forwardly and upwardly inclined frame 20, which may be formed by continuing the lower tubular rods 13 forwardly on converging lines, as shown in Fig. 1 and connecting their outer ends by a transverse member 21, whereby an open frame is formed, which frame, at its lower side, I cover with canvas, oiled silk, or other suitable material 22, so as to form a forwardly projecting upwardly inclined light member against which the air may act during the forward movement of the machine. The frame 20 may be strengthened or braced by means of rods 23 extending from the forward ends of the wooden sills or beams 14, to the outer ends of the rods 13, as indicated in Figs. 1 and 2. At the forward end of the frame 20 I pivotally mount a standard 24 to which is secured the rudder 25, which will be operated by the attendant on the seat 18 through cables or cords 26, the latter extending along the opposite sides of the machine and being connected at their front ends to the rudder 25 and at their other ends being connected to a windlass 27 in convenient relation to the seat 18. The cables or cords 26 after leaving the rudder 25 pass over pulley wheels 28 and thence extend along the opposite sides of the machine and finally pass over pulley wheels 29, whence said cables or cords pass directly to

the windlass 27, as more clearly indicated in Fig. 1. When the windlass is turned it will wind up on one cord or cable 26 and pay out the other cord or cable 26, and thus by means 5 of the one windlass the rudder 25 may be conveniently operated and kept under the absolute control of the attendant sitting on the seat 18.

At the rear end of the machine I preferably 10 provide a dove-tail shaped frame 30 consisting of side rods 31 and connecting sheet of canvas, oiled silk or other light material 32. The rods 31 will preferably be of flexible character and I prefer to construct them from 15 bamboo. The inner ends of the rods 31 are rigidly fastened to the rear ends of the longitudinal beams or sills 14, whence said rods diverge and incline rearwardly and downwardly, as indicated in Fig. 3. The frame 30 20 serves two purposes, one being to provide an effective surface for bearing downwardly against the air, and the other being to facilitate the steering of the machine. In order that the operator on the seat 18 may have 25 proper control of the frame 30, I provide two cords or cables 33 extending from the outer ends of the rods 31 to points adjacent to said seat, as shown in Fig. 1. The operator by pulling inwardly on both of the cords or cables 33 with equal force may vary the inclination 30 of the outer portion of the frame 30, turning said portion upwardly on a curved line, as indicated by the dotted lines in Fig. 2. The cords or cables 33 may also be independently 35 operated. When the attendant pulls on either one of the cords or cables 33, the outer corner of the frame 30 connected therewith will be curved upwardly thereby and the course of the machine varied accordingly. 40 The operator may therefore pull on both the cords or cables 33 simultaneously or on one at a time as he may desire. The frame 30 due to the fact that either outer corner of the same may be turned upwardly to meet the wind, 45 may be used for steering the machine and may be fully relied upon for this purpose should the rudder 25 for any reason become broken or disarranged. It is preferable to employ both the frame 30 and rudder 25, 50 since it might be desired to utilize the full bearing effect of the entire frame 30 and to steer the machine by means of the rudder 25 instead of making use of the frame 30 for steering purposes. 55 The wings 15 are utilized for propelling the machine and form an important part thereof. The wings 15 are arranged in sets of pairs, one pair being above another, at each side of the machine, as shown in Fig. 3, and the 60 wings on one standard 11 are alternated or out of horizontal alignment with the wings on the adjacent standards 11, as shown in Fig. 2. The wings 15 all correspond with one another in form and construction, and each comprises 65 a stiff transverse bar 34 and a vane composed

of a series of strong feathers or their equivalent 35 which are secured at their shank or quill ends to the bar 34 and thence extend rearwardly and preferably curve slightly downwardly (Figs. 1 and 2). The feathers 70 35 overlap one another and are spread to extend outwardly beyond the outer end of the bar 34, and in every detail of the feathers 35 I seek to imitate the arrangement of the feathers on the wing of a strong bird. I 75 have shown (Fig. 7) the bars 34 as curved and I will make them either straight or slightly arched, and preferably the bars 34 will be made hollow for securing lightness. In instances in which natural feathers cannot be 80 secured for the wings I will substitute as accurate an imitation for them as possible, such as a flexible frame of oiled silk or other light strong material secured to ribs representing the quills of the feathers. The oiled silk or 85 other fabric may be in strips secured to the ribs and overlapping in series, and in such instance the outer ends of all the strips should be secured to one another in series, so as to form an efficient wing and preserve the due 90 overlapping relation of the strips to one another during the operation of the wings; the inner ends of the strips should also be secured across their width.

The bars 34 for the pairs of wings are opposite to each other at opposite sides of the standards 11, as shown in Figs. 3, 4 and 5, and extend transversely of the machine, and said bars at their inner ends are fastened between upper and lower plates of hinges 36 95 (Figs. 4 and 5) which are secured to the standards 11 by means of pins 37. The inner ends of the hinges 36 are forked to pass partly upon the front and rear sides of the standards 11, and said hinges are formed with vertical 100 openings 38, which permit the passage through them of the cables or ropes 39, 40 by which the wings are operated, as hereinafter explained. The openings 38 in the hinges 36 also permit the wings to have a proper up 105 and down hinged movement and the walls of said openings may also form stops to contact with the standards 11 and prevent the folding upwardly of the wings against the sides of said standards should a breakage occur in 110 the cables 39, 40 or other accident happen whereby the wings should be left without proper control. The advantage of arresting the wings so that they may not fold vertically 115 upward in case of accident is to enable the 120 wings to form a parachute and prevent the descent of the machine with undue rapidity.

All of the wings on the machine are operated simultaneously by means of the auxiliary cables 39, 40 at each standard 11 and 125 the main cables 41, 42 extending lengthwise of the bed of the machine and to which all the cables 39, 40 are connected. The cables 41, 42 derive their fore-and-aft movements from a gasoline or other suitable motor 90. 130

All the wings at the outer side of each standard 11 are connected together and kept properly spaced apart by one reach of the cable 39, which is fastened to each of said wings 5 and extends upwardly over a top pulley 43, whence the other reach of the cable passes downwardly along the inner side of the standard 11 and through the openings 38 in the hinges 36; and all the wings at the inner side 10 of each standard 11 are likewise connected together and kept properly spaced apart by one reach of the cable 40 which is fastened to each of said wings and extends upwardly over a top pulley 44, whence the other reach 15 of said cable passes downwardly along the outer side of the standard 11 and through the openings 38 in the hinges 36 in its path. The inner reaches of the cables 39, 40 or those which lie close to the sides of the standard 20 11 are fastened together at a convenient point below the lower pair of wings and thence continue as a single cable 45 around under a pulley 46 (Fig. 6) and thence to and around a pulley 47 to the main cable 41 (or 42 as the case may be), to which the end of said cable 25 45 is securely fastened; and the outer reaches of the cables 39, 40 or those which are fastened directly to the wings are fastened together at a convenient point below the lower 30 pair of wings and thence continue as a single cable 48 around under a pulley 49 (Fig. 6) and thence to and around a pulley 50 (directly below pulley 47) to the main cable 41 (or 42 as the case may be) to which the end of said cable 35 48 is securely fastened so as to draw in the opposite direction to cable 45. With all of the cables 39, 40 at one side of the machine thus secured to the cable 41 and all of the cables 39, 40 at the other side of the machine 40 thus secured to the cable 42, it is obvious that on a forward movement of the cables 41, 42 they will by pulling on the inner reaches of all the cables 39, 40 and paying out the outer reaches of same effect the upward movement 45 of all the wings, and that on a rearward movement of the cables 41, 42 they will by pulling on the outer reaches of the cables 39, 40 and paying out the inner reaches of same effect the downward movement of all the wings. The cables 41, 42 by performing a reciprocating movement, are thus enabled to effect, 50 through the cables 39, 40, the proper up and down hinged movements of the wings. The pulleys 43, 44 are mounted in the standards 55 11 as shown in Figs. 4 and 5; the pulleys 46, 49 are mounted in straps 51 secured to the standards 11, and the pulleys 47, 50 are supported in the longitudinal sills 14.

The cables 41, 42 are more clearly shown in Fig. 1, in which it may be seen that said cables respectively pass around pulleys 52, 53 mounted on pins held by bars 54, and that the rear portions of said cables are brought together and the front portions of 60 said cables are brought together and all se-

cured to a single longitudinal cable 55, which is secured to a block or grip 56 carried by a pivoted lever 57 from which a fore-and-aft motion is imparted to the cable 55 and through it to the cables 41, 42 by which the 70 cables 39, 40 are actuated to operate the wings 15. The lever 57 is operated by means of any suitable crank or driving mechanism of usual character from the motor or engine 90, as shown in Fig. 2, which mechanism 75 being of well known character requires no special description. The lever 57 will have a uniform extent of stroke but the speed of this stroke may be varied or regulated from the engine or motor 90, and the extent of 80 movement to be imparted to the cable 55 and consequently to the wings 15 during each stroke of the lever 57 may be regulated by varying the position of the block or grip 56 with relation to the pivot point of the lever 85 57. The nearer the block or grip 56 is adjusted toward the fulcrum of the lever 57 the less will be the extent of movement imparted to the cables and wings by said lever. The block or grip 56 may be adjusted on the 90 lever 57 in various ways well understood by mechanics and any of these methods may be adopted. Usually the block or grip 56 will be slideable on the lever 57 and moved by a bell-crank lever operated by the attendant 95 from the seat 18. In the drawings I illustrate the block 56 as being in the form of a sleeve encompassing and slideable on the lever 57 and therefore capable of adjustment toward or from the fulcrum of said lever. 100

The operation of the machine will be largely understood from the detailed description hereinafter presented. The engine or motor 90 having been set in motion it will rock the lever 57 and this lever will through 105 the cables 55, 41, 42, 39, 40 actuate the wings 15 to drive or propel the machine. As soon as sufficient forward speed has been generated the machine will rise and be propelled through the air. The upwardly inclined frame 20 aids in the ascent of the machine; the rear frame 30 affords a bearing surface; the rudder 25 may be used for steering the machine, and the frame 30 may likewise be used for steering the machine and controlling 110 its position. The seat 18 is made slideable so that the operator may by moving said seat readily adjust the center of gravity of the machine. The wings 15 afford effective bearing surfaces and due to their construction exert a powerful influence in driving the machine forward. 115

All parts of the machine have been constructed and assembled with the view of securing great strength without unnecessary 125 weight and of producing a safe and efficient flying machine.

What I claim as my invention and desire to secure by Letters-Patent, is:—

1. In a flying machine, a body-frame hav- 130

- ing a series of standards at each side of the center thereof, and hinged propeller-wings mounted in pairs one above another on said standards, said wings each comprising a stiff bar and rearwardly extending vane, and said wings being adapted, when actuated, for propelling the machine through the air, combined with means for simultaneously actuating said wings, an upwardly inclined 5 forwardly extending covered frame 20 secured to the forward end of said body-frame below the horizontal plane of said wings and against which the air may act to aid in the ascent of the machine; a rudder for steering 10 the machine and means for operating said rudder; substantially as set forth.

2. In a flying machine, a body-frame having a series of standards at each side of the center thereof, and hinged propeller-wings mounted in pairs one above another on said standards, said wings each comprising a stiff bar and rearwardly extending vane, and said wings being adapted, when actuated, for propelling the machine through the air, combined 15 with means for simultaneously actuating said wings, an upwardly inclined forwardly extending covered frame 20 secured to the forward end of said body-frame below the horizontal plane of said wings and against which the air may act to aid in the ascent of the machine, a standard 24 mounted on the forward portion of said frame 20, a rudder 25 secured on said standard for steering the machine, and means for operating said rudder; 20 substantially as set forth.

3. In a flying machine, a body frame having standards at each side of the center thereof, and hinged wings mounted in pairs one above another on said standards, said pairs of wings being disposed so that the wings on one standard will be out of alinement with the wings on the adjacent standards, combined 25 with means for simultaneously actuating all of said wings; substantially as set forth.

4. In a flying machine, a body-frame having a series of standards at each side of the center thereof, and hinged propeller-wings mounted in pairs one above another on said standards, said wings each comprising a stiff bar and rearwardly extending vane, and said wings being adapted, when actuated, for propelling the machine through the air, combined 30 with means for simultaneously actuating said wings, an upwardly inclined forwardly extending covered frame 20 secured to the forward end of said body-frame below the horizontal plane of said wings and against which the air may act to aid in the ascent of the machine, a rudder for steering the machine, and a downwardly inclined tail-frame on the rear end of said body-frame below the horizontal plane of said wings; substantially as set forth.

5. In a flying machine, a body frame having standards at each side of the center thereof, 35 combined with means for operating said wings, an upwardly inclined frame having a covering thereon on the forward end of the machine, a downwardly inclined tail-frame on the rear end of the machine formed of flexible side rods connected by a fabric, and connections for deflecting said rods upwardly; substantially as set forth.

6. In a flying machine, a body-frame having standards at each side of the center thereof, and hinged wings mounted on said standards, combined with a motor carried by the machine, a longitudinally disposed cable 40 connected to receive a reciprocating movement from said motor, and cables connected to the opposite sides of said wings and to said longitudinal cable, whereby the latter is enabled to actuate said wings; substantially as set forth.

7. In a flying machine, a body-frame having standards at each side of the center thereof, and hinged wings mounted on said standards, combined with a motor carried by the machine, a longitudinally disposed cable mounted to have a reciprocating movement, a rocking lever to which said cable is connected and from which it receives its movements, means for actuating said lever from 45 said motor, and cables connected to the opposite sides of said wings and to said longitudinal cable, whereby the latter is enabled to actuate said wings; substantially as set forth.

8. In a flying machine, a body-frame having standards at each side of the center thereof, and hinged wings mounted on said standards, combined with a motor carried by the machine, a longitudinally disposed cable mounted to have a reciprocating movement, a rocking lever to which said cable is connected and from which it receives its movement, means enabling the adjustment of the point of connection of said cable with said lever toward or from the fulcrum of the lever for varying the stroke of the wings, means for actuating said lever from said motor, and cables connected to the opposite sides of said wings and to said longitudinal cable, whereby the latter is enabled to actuate said wings; substantially as set forth.

9. In a flying-machine, a body-frame having standards at each side of the center thereof, hinged wings mounted in pairs on said standards, means for actuating said wings, and stops for preventing said wings from folding unduly upwardly should their actuating means lose control of them; substantially as set forth.

10. In a flying machine, a body-frame having standards at each side of the center thereof, hinged wings mounted in pairs on said standards, combined with a motor car-

ried by the machine, a longitudinally disposed cable connected to receive a reciprocating movement from said motor, and cables connected to the opposite sides of said wings and to said longitudinal cable, whereby the latter is enabled to actuate said wings; substantially as set forth.

11. In a flying machine, a body-frame having standards at each side of the center thereof, hinged wings mounted in pairs on said standards and pulleys above and below the sets of wings, the hinges of said wings having vertical openings in them adjacent to said standards, combined with a motor carried by the machine, a longitudinally disposed cable connected to receive a reciprocating motion from said motor, cables at each of said standards passing over said pulleys and connected to said longitudinal cable and to the opposite sides of said wings, whereby the latter may be operated from said longitudinal cable, the reaches of said cables not directly connected with said wings being extended close along the sides of said standards and through said openings in said hinges; substantially as set forth.

12. In a flying machine, a body-frame comprising a set of hollow U-shaped frames set transversely, longitudinal bars connecting the horizontal members of said frames, and rods connecting the vertical members of said frames, said vertical members forming standards, combined with hinged wings mounted in pairs on said standards, and means for actuating said wings; substantially as set forth.

13. In a flying machine, a body-frame having standards at each side thereof, wings hinged in pairs on said standards, a sliding seat for the operator so that he may readily vary the center of gravity of the machine, means for actuating said wings, and means for steering the machine; substantially as set forth.

Signed at New York city, in the county of New York and State of New York this 13th day of October A. D. 1905.

MATTHEW NIAL.
